UNITED STATES PATENT OFFICE.

CHARLES R. WOOD, OF EDMONTON, ALBERTA, CANADA.

RULE POCKET.

Application filed March 29, 1924. Serial No. 702,855.

To all whom it may concern:

Be it known that I, CHARLES R. WOOD, a citizen of the United States, residing at Edmonton, in the Province of Alberta and Dominion of Canada, have invented certain new and useful Improvements in Rule Pockets, of which the following is a specification, reference being had to the accompanying drawings.

10 This invention relates to improvements in rule pockets and has for an important object thereof the provision of such a pocket including the desirable features of the pocket described in my Patent #1,407,827, granted February 28, 1922, for rule pockets, and in my co-pending application, Serial No. 685,220, filed January 9, 1924, for pocket constructions, to include in this pocket an inclined pocket opening with its accompanying advantages and without loss of the locking features of the pockets disclosed in said patent and application.

A further object of this invention is to provide a modification and improvement of 25 the type of pocket illustrated in my application, Serial No. 438,236, filed December 4, 1920, for safety pockets, and consists essentially in a modification of this pocket to enable construction of the pocket with an inclined pocket opening. It is well-known to 30 those familiar with the art that such inclined openings render access to the pocket much more readily than the ordinary vertical type of pocket opening and in addition present a much neater and pleasing appearance when the pocket is a patch pocket such as is employed upon overalls. Ordinarily such inclined openings cannot be employed for the reason that they provide a top opening 35 in the pocket through which rules, pliers or similar tools contained within the pocket would be obstructed during bending movements of the wearer of the garment thus rendering these tools likely to be lost from 40 the pocket.

A further object of the invention is to provide a pocket of this character which may be very cheaply and expeditiously employed and in which the construction of the 45 pocket is such that it lends itself readily to manufacture of the pocket from scraps of material otherwise wasted.

These and other objects I attain by the construction shown in the accompanying drawings, wherein for the purpose of illus-

tration is shown a preferred embodiment of my invention and wherein:

Figure 1 is a front elevation of a pocket constructed in accordance with my invention, the pocket being shown as having the 60 outer wall thereof formed of two pieces of material;

Figures 2 and 3 are modifications of the construction of the pocket wherein the outer wall of the pocket is formed of a single 65 piece of material;

Figures 4 and 5 are sections on the line 4—4 and 5—5 of Figure 1;

Figures 6 and 7 are sections on the line 6—6 and 7—7 of Figure 2;

Figures 8 and 9 are sections on the line 8—8 and 9—9 of Figure 3;

Figure 10 is a section on the line 10—10 of Figure 1, which section is characteristic of the three pockets shown in Figures 1 to 3;

Figure 11 is a section on the line 11—11 of Figure 2;

Figure 12 is a section on the line 12—12 of Figure 1, which section is also characteristic of a similar section through Figure 80 3;

Figures 13 and 14 are sections similar to those shown in Figures 4 and 5, the reinforcing piece at the bottom of the pocket being omitted.

Referring now more particularly to the drawings in Figures 1, 2 and 3 of which I have illustrated characteristic front elevations of pockets constructed in accordance with my invention, the numeral 10 indicates the inner wall of the pocket, 11 the outer wall, and 12 the lock. The pockets illustrated are of the rule pocket type and are primarily intended for this use although it will, of course, be obvious that by slight 95 modifications of the shape these pockets might be employed in other capacities. In the present instance the pocket is vertically elongated and tapers from top to bottom, the upper and lower edges of the pocket being 100 substantially parallel. The outer wall 11 of the pocket which may be formed of a single piece of material, as shown in Figures 2 and 3, or of two pieces of material, as shown in Figure 1, is of the shape of the completed 105 pocket with one upper corner thereof removed by a diagonal cut forming an upwardly and forwardly inclining edge 13. While I have stated that the edges are upwardly and forwardly inclining, it will be understood 110

that this description depends upon the application of the pocket to the side of the garment and is for the purposes of description only. The edges of the outer wall 11, with the exception of the edge 13, are stitched, as at 14, to the inner wall 10, the edge 13 being left free to provide access to the pocket. The lock 12 consists of a piece of material of greater length than the vertical length of the pocket opening. The upper edge 15 of this piece of material being aligned with the upper edge 16 of the outer wall and having a portion of the forward end thereof extended between the inner and outer walls and included in the stitching 14 connecting the upper edge of the outer wall to the inner wall. The rear edge 17 of the lock 12 aligns with the rear edge 18 of the pocket below the diagonal portion 13 thereof and has its lower end extended between the inner and outer walls 10 and 11 and included in the stitching 14 securing the portion 18 of the rear edge of the outer wall to the inner wall. Thus the front edge 19 and lower edge 20 of the lock piece are disposed within the pocket while a portion of the lock lies exteriorly of the pocket and combines with the outer wall 11 to give to the pocket its completed shape. Immediately below the lower end of the pocket opening the lock piece is secured to the outer wall by a longer horizontal line extending across the lock and generally indicated at 21. This securing means may take various forms as will hereinafter appear, the form indicated in Figure 1 being a simple line of stitching 22 connecting these walls together. By this construction the outer wall combines with the inner wall to provide a pocket having an opening O facing in one direction while the lock piece 12 and that portion of the outer wall lying beneath the lock piece within the pocket combine with the inner wall to provide a pocket having an opening O' of greater vertical length than the pocket opening O and opening in the opposite direction from the pocket opening O.

With this type of pocket where tools and heavy implements such as rules, pliers and the like are to be inserted in the pocket it is, of course, desirous that the pocket be reinforced at its lower end at the point where the pliers or rule rest. Where this reinforcing is applied interiorly, as indicated at 23 in Figures 4 and 5, and is secured to the outer wall of the pocket by stitching 24. I preferably terminate this reinforcement at the height at which the transverse connection 21 between the outer wall and the lock occurs and employ this stitching 24 to provide such connection. I have hereinbefore stated that the outer wall 11 of the pocket can be formed of one or more pieces of material. Where two pieces of material are employed 65 the connecting line between these pieces is

preferably arranged at the level of the connection 21 and the stitching employed to connect the pieces, indicated at 25, used to provide this connection. It will, of course, be obvious that, as indicated by the sectional view in Figures 4 and 8, this same stitching 25 in addition to securing the lock to the outer wall may be employed to secure the upper edge of a reinforcing strip 23 within the pocket at the lower end thereof. It will be noted that with the constructions hereinbefore set forth it is unnecessary that the lock be continued to the end of the pocket and that the effect of a lock so continued is provided. It will furthermore be noted that a pocket which is relatively wide at its upper end may be produced by the use of scrap material and without in any way detracting from the appearance or efficiency of the completed pocket. Many modifications of the pocket being possible without in any manner departing from the spirit of my invention, I do not limit myself to the structure hereinbefore set forth except as hereinafter claimed.

I claim:—

1. The combination with a vertically elongated pocket comprising inner and outer walls, the outer wall being secured about its edges to the inner wall with the exception of the upper portion of one vertical edge which is unattached to thereby provide a pocket opening, of a vertically elongated piece of material of greater length than the pocket opening having its upper edge aligned with the upper edge of the outer wall and having some portion of its upper edge inserted between the inner and outer walls at the upper end of the pocket opening and included in the connection of the upper edge of said outer wall to the inner wall, the lower end of the vertical edge of said piece of material corresponding to that edge of the outer wall having the unattached portion forming the pocket opening being inserted between the inner and outer walls at the lower end of the pocket opening and included in the connection of the lower end of said edge of the outer wall to the inner wall, the edge of said piece between the ends of the pocket opening being connected to the inner wall, and a horizontal connection between the outer wall and the piece extending across the piece at the lower end of the pocket opening, that portion of the edge of the piece of material attached to said inner wall lying exteriorly of the outer wall whereby the upper end of the completed pocket is wider than the upper end of the outer wall and whereby oppositely facing main and auxiliary pockets are provided, the auxiliary pocket opening into the main pocket and having its opening spaced transversely of the main pocket from the lower end of the opening of the main

pocket a distance equal to the width of the piece at the lower end of the pocket opening.

2. The combination with a vertically elongated pocket comprising inner and outer walls, the outer wall being secured about its edges to the inner wall with the exception of the upper portion of one vertical edge which is unattached to thereby provide a pocket opening, of a vertically elongated piece of material of greater length than the pocket opening having some portion of its upper edge inserted between the inner and outer walls at the upper end of the pocket opening and included in the connection of the upper edge of said outer wall to the inner wall, the lower end of the vertical edge of said piece of material corresponding to that edge of the outer wall having the unattached portion forming the pocket opening being inserted between the inner and outer walls at the lower end of the pocket opening and included in the connection of the lower end of said edge of the outer wall to the inner wall, the edge of said piece between the ends of the pocket opening being connected to the inner wall, and a horizontal connection between the outer wall and the piece extending across the piece at the lower end of the pocket opening, said outer wall being formed in two sections connecting on a line extending transversely of the pocket at the lower end of the pocket opening, the connection between the sections including and extending entirely across said piece of material and comprising said horizontal connection.
3. The combination with a vertically elongated pocket comprising inner and outer walls, the outer wall being secured about its edges to the inner wall with the exception of the upper portion of one vertical edge which is unattached to thereby provide a pocket opening, said unattached portion inclining upwardly toward the other vertical edge of the pocket, of a vertically elongated piece of material of greater length than the pocket opening having the forward portion of its upper edge inserted between the inner and outer walls at the upper end of the pocket opening and included in the connection of the lower end of the edge of the outer wall to the inner wall, said vertical edge of said piece of material inclining oppositely from the unattached edge portion of the outer wall and being secured to the inner wall throughout its length, a connection between the outer wall and the piece of material at the lower end of the pocket opening extending across the piece of material, and a reinforcing piece located in the lower end of the pocket and having its side and bottom edges included in the stitching connecting the sides and bottom of the outer wall to the inner wall, the upper edge of said reinforcing piece extending between the inner wall and the piece of fabric and being included in the horizontal connection between the fabric piece and the outer wall.
4. The combination with a vertically elongated pocket comprising inner and outer walls, the outer wall being secured about its edges to the inner wall with the exception of the upper portion of one vertical edge which is unattached to thereby provide a pocket opening, said unattached portion inclining upwardly toward the other vertical edge of the pocket, of a vertically elongated piece of material of greater length than the pocket opening having the forward portion of its upper edge inserted between the inner and outer walls at the upper end of the pocket opening and included in the connection of the upper edge of said outer wall to the inner wall, the remainder of the upper edge of said piece of material being secured to the inner wall, the lower end of the vertical edge of said piece of material corresponding to that edge of the outer wall having the unattached portion forming the pocket opening being inserted between the inner and outer walls at the lower end of the pocket opening and included in the connection of the lower end of the edge of the outer wall to the inner wall, said vertical edge of said piece of material inclining oppositely from the unattached edge portion of the outer wall and being secured to the inner wall throughout its length, a connection between the outer wall and the piece of material at the lower end of the pocket opening extending across the piece of material, and a reinforcing piece located in the lower end of the pocket and having its side and bottom edges included in the stitching connecting the sides and bottom of the outer wall to the inner wall, the upper edge of said reinforcing piece extending between the inner wall and the piece of fabric and being included in the horizontal connection between the fabric piece and the outer wall.
5. The combination with a vertically elongated pocket comprising inner and outer walls, the outer wall being secured about its edges to the inner wall with the exception of the upper portion of one vertical edge which is unattached to thereby provide a pocket opening, of a vertically elongated piece of material of greater length than the pocket opening having some por-

tion of its upper edge inserted between the inner and outer walls at the upper end of the pocket opening and included in the connection of the upper edge of said outer wall to the inner wall, the lower end of the vertical edge of said piece of material corresponding to that edge of the outer wall having the unattached portion forming the pocket opening being inserted between the inner and outer walls at the lower end of the pocket opening and included in the connection of the lower end of said edge of the outer wall to the inner wall, the edge of said piece between the ends of the pocket opening being connected to the inner wall, a horizontal connection between the outer wall and the piece extending across the piece at the lower end of the pocket opening, said outer wall being formed in two sections connecting on a line extending transversely of the pocket at the lower end of the pocket opening, the connection between the sections including and extending entirely across said piece of material and comprising said horizontal connection, and a reinforcing piece located in the lower end of the pocket and having its side and bottom edges included in the stitching connecting the sides and bottom of the lower section of the outer wall to the inner wall, the upper edge of said reinforcing piece likewise being included in the connection between the sections of the outer wall.

6. The combination with a vertically elongated pocket comprising inner and outer walls, the outer wall being secured about its edges to the inner wall with the exception of the upper portion of one vertical edge which is unattached to thereby pro-

vide a pocket opening, of a vertically elongated piece of material of greater length than the pocket opening having some portion of its upper edge inserted between the inner and outer walls at the upper end of the pocket opening and included in the connection of the upper edge of said outer wall to the inner wall, the lower end of the vertical edge of said piece of material corresponding to that edge of the outer wall having the unattached portion forming the pocket opening being inserted between the inner and outer walls at the lower end of the pocket opening and included in the connection of the lower end of said edge of the outer wall to the inner wall, the edge of said piece between the ends of the pocket opening being connected to the inner wall, a horizontal connection between the outer wall and the piece extending across the piece at the lower end of the pocket opening, said outer wall being formed in two sections connecting on a line extending transversely of the pocket at the lower end of the pocket opening, the connection between the sections including said piece of material and comprising said horizontal connection, and a reinforcing piece located in the lower end of the pocket and having its side and bottom edges included in the stitching connecting the sides and bottom of the lower section of the outer wall to the inner wall, extending between the inner wall and the piece of fabric and being likewise included in the connection between the sections of the outer wall.

In testimony whereof I hereunto affix my signature.

CHARLES R. WOOD.
